UNITED STATES PATENT OFFICE.

THOMAS A. RIDDER, OF WOLLASTON, MASSACHUSETTS.

RADIATOR.

Application filed March 6, 1926. Serial No. 92,896.

This invention relates to radiators of the type used to heat buildings.

The radiators now in use are commonly provided with legs or feet that rest upon the floor to support the radiator in spaced relation to the floor, and the heating fluid is commonly conducted to and from the radiator by exposed pipes that extend upwardly through the floor to the points where they are connected to the radiator.

These radiator pipes are more or less unsightly, and they as well as the radiator supporting legs, constitute obstructions about which it is difficult to clean or remove the dirt and dust.

An important feature of the present invention therefore resides in a novel construction whereby the radiator supporting legs are made hollow so that the fluid for heating the radiator may be supplied thereto through the legs. As a result of this construction the radiator pipes are entirely concealed and the supporting legs are given a construction that is pleasing in appearance and about which the dirt and dust may be much more easily removed than heretofore.

It is desirable to locate the valve which controls the flow of fluid through the radiator in an elevated position to increase its accessibility and it has therefore been proposed heretofore to mount this valve in the upper part of a radiator section, but in order to place the valve in this position it has been customary heretofore to provide a pipe outside of the radiator which extends upwardly to the valve, and which is more or less unsightly; or the heating fluid has been led upwardly through the entire first section of a radiator to the valve, in which case the heating fluid cannot be excluded from this first section by closing the valve.

Another feature of the present invention therefore resides in the construction whereby the first section of the radiator is provided with a separate conduit formed in a portion thereof and which is adapted to conduct the heating fluid from a supply pipe to the valve at the upper end of the section. As a result of this construction the valve will serve to cut off the heating fluid from part of this first section as well as from the other sections of the radiator.

Other features of the invention and novel combination of parts in addition to the above will be hereinafter described in connection with the accompanying drawings

which illustrate one good practical form of the invention.

In the drawings:

Fig. 1 is a side elevation of a radiator 60 constructed in accordance with the present invention;

Fig. 2 is partly an end view of the left hand end of the radiator of Fig. 1, and partly a sectional view taken on the line 2—2 65 of Fig. 1; and

Fig. 3 is a sectional view taken on the line 3—3 of Fig. 2.

The radiator with which the present invention is associated may for the most part 70 have any preferred or well known construction, and the heating fluid for the radiator may be steam or hot water, as is usual.

The radiator shown consists of a series of connected intermediate heat radiating sections 10 which may have the usual or any preferred construction, and at one end of the radiator sections 10 is secured the end section 11, while at the opposite end is secured the end section 12.

In the construction shown the section 12 constitutes the fluid inlet section and the section 11 the outlet section, but the present invention is not necessarily limited in its use to radiators of the type shown, having 85 separate inlet and outlet conduits, since certain features of the invention may be employed in connection with radiators of the type having a single conduit which serves as both inlet and outlet for the heating fluid.

As stated, one of the features of the present invention resides in the construction whereby the supporting legs of the radiator are made hollow so that the heating fluid may be supplied to the radiator through the 95 legs.

In the construction shown the radiator section 12 is provided at its lower end with a downwardly extending boss or nipple 13 which is internally threaded to receive the short tube 14 that forms the upper part of a union. To the short tube 14 is secured the base leg 15 which constitutes the lower portion of the union, and the portions 14 and 15 are secured together by a union nut 16 which may have the usual or any preferred construction. The base leg 15 is provided with a flange portion 17 that rests on the floor and which flares outwardly in a direction transversely of the radiator, as shown, to provide a firm support for the 105 radiator. The rounded outwardly flaring type of base shown is desirable as it is pleas-

ing in appearance, and dirt and dust may be readily removed from around the same.

The lower end of the base leg 15 is preferably threaded as shown so that it may be 5 screwed onto a supply pipe 18 that the heating fluid may pass from the supply pipe 18 upwardly through the conduit 19 to the radiator section 12. The construction is such that the base section 15 may be screwed 10 onto the pipe 18 and then the radiator may be secured to this section by tightening the union nut 16.

The hollow leg at the opposite end of the radiator may be similar in construction to 15 the leg just described and serves to support the right-hand end of the radiator and also to form a conduit leading from the lower end of the section 11 to the return pipe 20.

The means just described for supporting 20 a radiator and supplying the heating fluid to the same constitutes an extremely simple construction which is inexpensive to construct and install, and by concealing the supply and return pipes the radiator is given 25 a more pleasing appearance and the floor around the supporting legs may be more easily cleaned than heretofore.

The valve for controlling the supply of 30 heating fluid to the radiator may be located in various positions as desired, and in the construction shown the fluid control valve 21 is located near the upper end of the radiator where it may be easily reached without stooping or leaning over. It is desirable 35 that the valve 21 serve not only to cut off the supply of heating fluid to the sections 10 and 11, but that it serve also to cut off the heating fluid to a portion of the inlet section 12. To this end, in accordance with 40 the present invention, the section 12 is divided longitudinally by providing the same with the inner wall 22 that extends upwardly from the inlet nipple 13 to form the conduit 23. At the upper end of the conduit 45 23 is provided the transversely extending wall 24 with which the valve 21 cooperates, and the arrangement is such that when this valve is open the heating fluid may enter the portion 25 of the section 12 (see Fig. 50 3) and may pass through the bore 26 to the intermediate sections 10. The valve 21 may have any usual or preferred construction and is operated by the handle 27. The return radiator section 11 is preferably provided 55 near its lower end with a trap valve

28 which is constructed to retain steam within the radiator, while it will open to permit water to escape therefrom. These trap valves heretofore have been mounted in a valve casing outside of the radiator where 60 they form a connection between the radiator section and return pipe.

In accordance with the present invention the radiator section 11 is provided with an interior wall 29 constructed to form a valve 65 seat and this wall is so disposed within the radiator section that it forms a pocket within the section adapted to receive the valve 28, the arrangement being such that the trap valve 28 is entirely housed within the radiator section instead of being mounted outside of the section as heretofore.

What is claimed is:

1. A radiator, comprising in combination, 70 a series of connected heat radiating sections, one of said sections being divided vertically by an interior wall to form a separate conduit at one side of the section, a vertically disposed inlet port formed centrally of the lower end of said section, said wall being 80 bent at its lower end to form a curved passage communicating with the vertically disposed inlet port, a valve at the upper portion of said conduit for controlling the passage of fluid from the conduit into the remaining portion of the section, a hollow leg 85 having a pedestal for supporting the section from the floor and provided with a fluid passage leading to said port, and means for connecting the leg to a source of fluid supply. 90

2. A radiator, comprising in combination, 95 a series of connected heat radiating sections, one of said sections being divided vertically by an interior wall to form a separate conduit at one side of the section, a vertically disposed inlet port formed centrally of the lower end of said section, said wall being laterally displaced adjacent its lower end to form a passage communicating with the vertically disposed inlet port, a valve associated with said conduit for controlling the passage of fluid from the conduit into the remaining portion of the section, a hollow leg having a pedestal for supporting the section from the floor and provided with a fluid 100 passage leading to said port, and means for connecting the leg to a source of fluid supply. 105

In testimony whereof, I have signed my name to this specification.

THOMAS A. RIDDER.
